PANEL FOR LAUNDRY APPLIANCES

Stuart G. Mundt, North Syracuse, N. Y., assignor, by mesne assignments, to The Murray Corporation of America, Detroit, Mich., a corporation of Delaware

Application May 11, 1955, Serial No. 35,927

Term of patent 14 years

(Cl. D49—1)

FIG. 1.

FIG. 2.

FIG. 3.

FIG. 4.

I claim:

The ornamental design for a panel for laundry appliances, substantially as shown.
